UNITED STATES PATENT OFFICE.

ALEXANDER KRAUS, OF NEW YORK, N. Y.

HOLDER FOR KNITTING AND SIMILAR NEEDLES.

Application filed October 16, 1922. Serial No. 594,683.

To all whom it may concern:

Be it known that I, ALEXANDER KRAUS, a citizen of the United States, and a resident of the city and State of New York, have invented certain new and useful Improvements in Holders for Knitting and Similar Needles, of which the following is a specification.

My invention relates to means for attachment to a knitting, crochet or other needle for the purpose of holding the needle to the work when not in use and for preventing the unravelling of the fabric between knitting or crocheting operations. Where a woman is knitting or crocheting by hand she usually stops at various intervals and puts the knitting aside and she either withdraws the needle or needles from the fabric or else sticks the point of the needle into the fabric or into the ball of yarn to keep it from being lost or misplaced. When the needle is withdrawn from the yarn or fabric it is likely to and often does injure the yarn or draw on one of the loops of the fabric. It is not always convenient to hold open or retain the last loop or loops of the fabric from pulling out and the fabric is often partially unravelled when laid aside between knitting operations. The object of my invention is to provide simple means for attachment to the needle which will engage and hold the last loop or loops of the fabric whereby the needle will not be displaced or lost and whereby the stitches will be prevented from unravelling. The present device is simple, inexpensive and it is very easy to use, and, if desired, it may serve to protect the hook of the needle from catching in the yarn and in other objects.

In the drawing forming part of this application,

Figure 1 is a side view of a knitting needle having my invention applied thereto, Figure 2 is a sectional view thereof taken on the line 2—2 of Figure 1,

Figure 3 is a plan view thereof,

Figure 4 is a side elevation of a modified form,

Figure 5 is a sectional view taken on the line 5—5 of Figure 4,

Figure 6 is a side elevation of my device adapted for a pair of needles, and

Figure 7 is a sectional view thereof taken on the line 7—7 of Figure 6.

The device consists principally of a sleeve

adapted to be slid onto the end of the needle and of a hinged finger for locking over the loop of the fabric. This finger may lock on the pin itself or upon the sleeve or, in the use of device for a pair of needles it may lock on both needles, these several modifications being illustrated in the drawing.

Referring first to the form shown in Figures 1, 2 and 3, there is a sleeve 1 which has a bore 2 and this sleeve is adapted to be slid onto one end of the knitting or crochet needle 3. If this sleeve is placed on the butt end of the needle as shown in Figure 1 then the device merely acts as a holder, whereas, if it is placed over the hook end of the needle it also acts as a guard to prevent the hook catching into the yarn, the clothes or to any bag into which the work may be placed. The sleeve 1 therefore may be placed on either end of the needle, and in this form the end 4 of the sleeve is closed to engage the end of the needle and thereby limit the positioning of the sleeve on the needle or to guard the hook. This sleeve may be detachably secured to the needle by friction or it may be permanently fixed thereto but the former is preferable because then the sleeve may be removed from the needle when the latter is to be used. The sleeve 1 is provided with a pair of upstanding ears 5, between which is hinged or pivoted one end of a finger 6, a hinge pin 7 securing these members together. This finger 6 is shown as arched or bowed as a preferred form so that for the greater part of its length it stands out or is spaced from the needle. At its free end the finger 6 has a pair of downwardly extending lugs 8 which in this form clip over or snap onto the needle 3. These lugs are so shaped and proportioned that they are forced apart when pressed onto the needle and when the finger is in the full line position shown in Figure 1 these lugs 8 extend below the plane of the axis of the needle. They may even engage partly around the needle as shown at 9 so that the finger 6 will not disengage from the needle by a slight or accidental pressure and the yarn will not slip through between the needle and finger.

As stated above, the device may remain on the needle at all times or it may be slipped on only when the work is to be laid aside. When the user stops knitting

or crocheting she simply lifts up the free end of the finger 6 and then passes the yarn 10 along the needle and under the finger. Then the finger is pressed down onto the 5 needle until the lugs 8 snap over and lock on the needle and hold the finger 6 closed or locked as shown in Figures 1, 2 and 3. The loop 10 can not now slide off either end of the needle because the arched finger 6 10 will prevent the loop from passing it at each end. If desired, the free end 11 of the yarn may be wound around the needle. By means of this holder the needle is secured to the fabric against loss and the last 15 loop 10 is locked so that the fabric will not unravel before the selvage or locking stitches have been made.

In Figures 4 and 5 I have shown a modified form of my device. In this form the 20 sleeve 12 is shown longer and on this is arranged an outer sleeve 13 fixed to the former sleeve. This outer sleeve has the ears 5 to which the finger 6 is pivoted. In this form, however, the finger 6 and the lugs 8 engage 25 the sleeve 12 instead of the needle. Otherwise the construction and operation are the same as in the first form.

In Figures 6 and 7 I have shown the device adapted for a plurality of needles, such 30 as a pair of long celluloid or bone needles commonly used for knitting. In this case the sleeve 14 is oblong in cross section and is large enough to fit snugly over two parallel needles 15. The ears 5 as in the other 35 forms, have pivoted to them the finger 6. In this case the finger has lugs 8 spaced apart sufficiently to straddle both needles 15 and to snap over the sides of these and engage below the planes of their axes, as is shown 40 in Figure 7. In using this form the sleeve 14 is simply slid over the ends of the parallel needles and the sleeve then holds

the needles together. The finger 6 is used to lock the yarn loop on the needles the same as in the first form.

45

It will be obvious that other forms may be used so long as the locking feature is used to lock the thread on the needle or needles.

Having described my invention, what I 50 claim is:—

1. A device for securing a needle temporarily to the work comprising a needle and a pivoted finger connected at one end to the needle, and having its free end movable in relation to the needle, and locking means on the free end of said finger whereby to lock said finger over a yarn loop surrounding the needle and preventing said loop from moving off either end of the 60 needle.

2. A device for securing a needle temporarily to the work comprising a needle having a finger pivotally connected with the needle at one end, said finger being 65 movable in relation to the needle, and members on the free end of said finger adapted to be sprung over the needle to lock thereon whereby said finger will lock a loop of yarn surrounding said needle from moving 70 off the ends of the needle.

3. A device for securing a needle temporarily to the work comprising a sleeve fitting over and held on the needle and a pivoted finger movable in relation to the needle 75 and having members on its free end adapted to be sprung over the needle to lock thereon whereby said finger will lock a loop of yarn surrounding said needle from moving 80 off the ends of the needle.

Signed at the city, county, and State of New York this 10th day of October, 1922.

ALEXANDER KRAUS.
